THERMIONIC CONTROL DEVICE

Ross Gunn, Washington, D. C.

Application November 13, 1931, Serial No. 574,733

13 Claims. (Cl. 250—27.5)

(Granted under the act of March 3, 1883, as
amended April 30, 1928; 370 O. G. 757)

This invention relates to a thermionic control device and more particularly to one adapted for use in modulating radio waves.

The object of my invention is to provide a device of the type mentioned that has double control circuits whereby the high frequency oscillations and the low voice frequencies may be completely separated in a modulating circuit, one thereof being magnetically controlled and the other being electrostatically controlled.

With the above and other objects in view, the invention consists in the construction, combination and arrangement of parts as will be herein-after more fully described.

Reference is to be had to the accompanying drawings forming a part of this specification in which like reference characters indicate corresponding parts throughout the several views and in which:

Fig. 1 is a perspective view of the embodiment of my invention at present preferred;
Fig. 2 is a diagram of one circuit in which my invention may be advantageously used.
The envelope 4 of the tube is adapted to be exhausted to the requisite degree. Disposed therein is a hot cathode 5 surrounded by a control grid 6 having the external connection 7. A set 8 of deflecting plates is interposed on each side of grid 6 between the grid and the anode plates 9. The deflecting plates in a set may be all connected into a single group, or the alternate plates in a set may be connected together, as indicated in Fig. 2 and shown in Fig. 1 to make two groups 10 and 11 in each set, the corresponding groups being connected together as shown in Fig. 1 which latter is in effect a multi-plate condenser. When suitable potentials are impressed upon the deflecting plates and varied in any desired manner, the fluctuations imposed by grid 6 upon the electron stream from filament 5 to plates 9 will be modified by the diversion of a greater or less proportion of the electrons away from the plates 9 to the deflecting plates 8.

The application of my invention as shown in Fig. 2 involves coupling coils 12 and 13, the former being the input primary and the latter being the secondary connected in circuit with grid 6 and grid biasing battery 14. Filament 5 is heated by current from a source 15 and is connected to plate group 10 by a by-pass condenser 16. Battery 17 and secondary coil 18 are connected in series between groups 10 and 11 of the deflecting plates. Batteries 19 and 20 are connected between cathode 5 and output primary coil 21, a median tap 22 from coil 18 being connected be-

tween them. By-pass condenser 23 is connected between coil 21 and filament 5. Coil 24 is the output secondary.

The passage of electrons from cathode 5 to anode 9 is controlled by the voltages impressed upon grid 6 by input coils 12 and 13, the electrons impinging upon anode 9 producing the plate current. Battery 17 sets up an electrostatic field between the plates of sets 10 and 11, the positively charged plates of the former attracting the electrons and the negatively charged plates repelling them toward the positively charged plates, so that the number passing through to plate 9 is much reduced. When a fluctuating current is caused to pass through coil 25, as by connecting it to a microphone that is subjected to sound waves, currents will be induced in coil 18 that will modify the charges on plates 10 and 11, at times increasing the charge so that very few electrons will reach plate 9, at other times decreasing the charge so that large numbers will pass to plate 9 and a strong plate current will flow through output coil 21. There will be a positive bias on the sets of the deflector plates 8 as a whole, due to battery 19, and a much stronger positive bias on the plate due to the series action of batteries 19 and 20, so that the electrons will be drawn from filament 5 toward them, but the number that reaches plate 9 will be determined by the condition of the electrostatic field between the plates of sets 10 and 11. The effect of this action is that the oscillations in the plate current due to grid 6 will be modulated by the changes in the electrostatic field produced by the fluctuations in coil 25.

It is to be understood that the present invention has many other uses than herein specified, as, for example, it may be used to divide or multiply frequencies or as a straight amplifier, the constructions and uses herein set forth being by way of illustration merely and not by way of limitation.

The herein described invention may be manufactured and used by or for the Government of the United States for governmental purposes without the payment to me of any royalties thereon.

Having thus described my invention, what I claim is:

1. A thermionic tube comprising a cathode, a control grid disposed therearound, an anode having sections on opposite sides of said grid, and a set of spaced apart plates between each anode section and said grid, each of said sets comprising two groups of plates having the plates

- in each group connected together and to the corresponding group in the other set.
2. A thermionic tube, comprising a cathode, a control grid disposed therearound, an anode having sections on opposite sides of said grid spaced therefrom, all in the same evacuated space and a plurality of spaced apart plates alternately connected together into groups disposed between each anode section and the said grid.
3. A thermionic tube, comprising a single element cathode, an anode spaced therefrom, a grid between said cathode and said anode, all in the same evacuated space, and a plurality of spaced apart plates alternately connected together into two groups disposed between said grid and said anode.
4. A thermionic tube, comprising an electron emissive element, means for collecting electrons so emitted, means for controlling the stream of electrons from said element to said first mentioned means, and means for diverting the said stream of electrons, the last mentioned means having a plurality of spaced parallel plates with the alternate plates connected to be chargeable with opposite electrostatic charges.
5. A thermionic tube comprising an anode, a cathode, a control grid and an additional control means, said means comprising a plurality of imperforate plates disposed between said control grid and said anode spaced apart and parallel to the principal direction of flow of the electrons from the cathode to the anode there being a plurality of pairs of plates constituted thereby, the plates of each pair being adapted to be oppositely charged and each of said plates save the outermost two being a member of two such pairs.
6. A thermionic device, comprising a tube having a source of electrons, a collector of electrons, control means to vary the flow of electrons from said source to said collector and a series of parallel plates between said source and said collector connected to constitute in effect a plurality of pairs of oppositely chargeable plates constituting additional control means to modulate the electron stream.
7. A thermionic tube, comprising a cathode, an anode spaced therefrom, a grid between said cathode and said anode and a plurality of spaced apart imperforate plates connected together to constitute a plurality of pairs of plates with the plates of each pair oppositely chargeable disposed between said grid and said anode.
8. A thermionic tube, comprising an anode, a cathode, a control grid and an additional control means, said means comprising a plurality of pairs of imperforate plates disposed between said control grid and said anode spaced apart and parallel to the principal direction of flow of the electrons from the cathode to the anode.
9. A thermionic tube, comprising a cathode, a substantially helical grid disposed around said cathode, and an anode, all in the same evacuated space, means in said tube between said grid and said anode to deflect electrons passing from said cathode to said anode, said means including a plurality of plates parallel to each other and disposed at an angle to said anode, the alternate plates being connected together.
10. A thermionic tube including a cathode, a substantially helical grid disposed around said cathode, and an anode, all in the same evacuated space, said grid being adapted to control the flow of electrons from said cathode to said anode, and means between the grid and the anode having portions that in effect constitute a multi-plate condenser with the planes of the plates parallel to the electron stream.
11. A thermionic tube, comprising a source of electrons, means therein to control the flow of said electrons, an anode having two sections on opposite sides of said source, and means in said tube having two portions each of which portions constitutes in effect a multi-plate condenser to modify the control flow of said electrons by application of opposite electrostatic charges to adjacent elements of said portions, the last said means being disposed between the sections of the anode.
12. A thermionic tube, comprising a cathode, a control grid disposed therearound, an anode having sections on opposite sides of said grid and spaced therefrom, all the aforesaid elements being in the same evacuated space, and a plurality of spaced apart plates alternately connected together into groups disposed between each anode section and said grid to deflect electrons passing therebetween and to hold a portion of such electrons, the proportion of electrons so held being a function of the voltage impressed upon said plates.
13. A thermionic tube, comprising a single element cathode, an anode having two sections on opposite sides of said cathode, a plurality of pairs of plates disposed between each anode section and said cathode and a single-wire grid to control the flow of electrons from said cathode to both anode sections.
